UNITED STATES PATENT OFFICE.

WILLIAM G. KENDALL, OF NEWARK, NEW JERSEY.

COMPRESSED-POWDER HOLDER.

1,223,985.

Specification of Letters Patent. Patented Apr. 24, 1917.

Application filed July 31, 1916. Serial No. 112,348.

To all whom it may concern:

Be it known that I, WILLIAM G. KENDALL, a citizen of the United States, residing at Newark, in the county of Essex and State 5 of New Jersey, have invented certain new and useful Improvements in Compressed-Powder Holders, of which the following is a specification.

My invention relates to new and useful 10 improvements in compressed powder holders, the primary object of my invention being the provision of a simple and improved method of packaging toilet powder, rouge and similar articles in compressed form.

15 More specifically, my invention includes an ornamental box or container, preferably formed of sheet metal and means lockingly held in the box for detachably securing a pad holding a cake of powder so that after 20 the powder has been used from the pad the pad may be withdrawn and replaced by a fresh one.

In this connection a still further object 25 of my invention consists in providing a device which is detachably applied within the box and which will detachably and lockingly receive a powder holding pad.

Another object of my invention is to provide an anchoring device of the above described 30 character of such construction that it may be stamped or otherwise formed in a single piece from sheet metal or other suitable material.

With these and other objects in view my 35 invention will be more fully described, illustrated in the accompanying drawings and then specifically pointed out in the claims which are attached to and form a part of this application.

40 In the drawings:

Figure 1 is a central vertical sectional view taken through a container equipped with my compressed powder holding device, the powder holding pad and the anchoring means being shown in elevation;

Fig. 2 is a perspective view of the anchoring device with the powder pad applied;

Fig. 3 is a section corresponding to Fig. 1, 50 illustrating a modified form of construction;

Fig. 4 is a perspective view of the form of construction shown in Fig. 3;

Fig. 5 is a view corresponding to Figs. 1 55 and 3, illustrating a still further construction; and

Fig. 6 is a perspective view of the anchoring device shown in Fig. 5.

Corresponding and like parts are referred to in the following description and indicated in all the views of the drawings by the same reference characters.

In Fig. 1 of the drawings I have illustrated a container in the form of a sheet metal box 10 having a circular bottom 11 and upstanding side walls 12, the latter being flared somewhat from its lower to its upper edge for a reason which will be later apparent. The upper portion of the side wall 12 is inset somewhat to provide 15 an annular stop shoulder 13 exteriorly of the box and a cover 14 is hinged to the box at one side as shown at 15 and is formed with a depending flange 16 adapted to engage about the reduced upper portion of the 20 box and to abut against the stop shoulder 13 when the box is closed. That portion of the flange 16 opposite the hinge 15 may be outstruck to form a projection 17 to facilitate opening of the cover and also to provide 25 a resulting interior depression to lockingly receive a correspondingly outstruck portion 18 of the wall of the box and thereby provide a frictional lock for the cover. Mounted within the box is a mirror 19 secured by a ring 20 which is wedged within the flange 16, injury to the mirror due to 30 forcing of the ring against it upon closing of the box being prevented by engagement of the flange 16 of the cover with the stop shoulder 13. An eye 21 is preferably secured to the box below the hinge and carries 35 a ring 22 by means of which the box may be suspended from a chain.

My present invention consists primarily 40 in providing means for securing a powder or rouge holding pad 23 within the above described box. As clearly shown in Figs. 1 and 2 of the drawings this pad is circular in shape, being formed with an upwardly 45 and inwardly directed peripheral wall 24 which lockingly receives powder or rouge pressed against the upper face of the pad as indicated at 25. As a means for anchoring this pad within the box I provide a device indicated as a whole by the numeral 26 in the form of a disk of relatively light 50 resilient metal or other material proportioned to fit snugly within the lower portion of the box so that its peripheral edges 55 will be wedged against the inner face of the wall 12 of the box and the device thus held

in place. This disk 26 is provided at peripherally spaced intervals with outwardly directed ears, substantially rectangular in shape and at either side of these ears is 5 radially slotted as shown at 27 in order that the ears, together with the portions comprehended between the slots may provide resilient tongues 28 which when bent up in the manner shown in Figs. 1 and 2 10 will lie within the peripheral boundary of the disk. As shown these tongues are bent inwardly to extend at an acute angle to the base or disk 26 and their free ends are sprung outwardly somewhat to facilitate application of the pad as will be later apparent.

After the anchoring device or holder 26 has been forced into place in the bottom of the box 10 a powder or rouge filled pad 20 is positioned in the box and pressure brought to bear against it to force it between the ends of the tongues 28 and into engagement with the disk 26. When so positioned the tongues spring in against the 25 upwardly and inwardly inclined peripheral wall of the pad and securely anchor it in place. Obviously the pad when emptied may be removed by inserting a suitable instrument such as a knife blade or scissor 30 blade between its edge and the wall of the box and prying the pad out. Three or more anchoring tongues may be provided but I have found that four of these tongues afford sufficient anchoring means for the pad and 35 at the same time permit of more ready removal when desired.

In Figs. 3 and 4 of the drawings I have illustrated a modified form of structure including a box 29 having a circular bottom 40 30 and an upstanding preferably vertical marginal wall 31 provided intermediate its height with an outstruck annular bead to form a stop shoulder 32. Coöperating with this box is a cover 33 having a marginal 45 flange 34 adapted to engage about the upper end of the box and seat against the stop shoulder or flange 32. A mirror 35 is located within the cover and secured by a ring 36 wedged within the flange 34, this 50 construction being the same as that described in connection with the form of the invention shown in Fig. 1. The device for anchoring or detachably securing the powder or rouge holding pad 23 in this form 55 of container is best shown at 37 in Fig. 4 and includes a disk shaped body member provided with peripherally spaced, radially extending arms 38 the free ends of which are upturned as shown at 39 to provide 60 locking fingers the terminals of which are outstruck. This disk may be lightened by cutting away its central portion as shown at 40, which is also true of the disk 26 previously described. The holder 37 is positioned in the box as shown in Fig. 3, fitting

relatively loosely therein. The powder holding pad 23 is then inserted in the box and forced between the fingers 39 in order that the insprung intermediate portions of such fingers may snap over the flared lower 70 portion of the pad and anchor it in place. This insertion of the pad between the fingers slightly spreads the fingers with the result that their outturned terminals seat in the peripheral groove provided interiorly 75 of the box by the formation of the stop shoulder 32 and consequently serve to lock the holder within the box.

In Fig. 5 I have illustrated a still further form of construction in which the container or box is preferably formed of cardboard including a circular bottom 41 having an inner peripheral wall 42 and an outer peripheral wall 43 of less height than the inner wall whereby an exterior stop shoulder 44 is provided to receive the annular flange 45 of the cover 46 when the latter is closed. This cover may be either hinged to the box or not as preferred and a clamping ring 47, also of cardboard, engages 80 within the flange 46 and secures a mirror 48 in place. The anchoring member employed in connection with this box is intended for use in securing a somewhat modified form of powder or rouge holding pad 85 in place and is best illustrated in Fig. 6. This member includes a disk shaped body 49 provided at peripherally spaced intervals with radially extending tongues 50 which in spaced relation to the edge of the body 100 are bent upwardly as shown at 51. The powder holding pad, as shown in Fig. 5, includes a circular base 52 surrounded by an upstanding marginal flange 53 which may or may not be inwardly flared, as preferred. This pad is inserted between the upwardly directed arms of the holder 49 and the terminals of the arms are then bent inwardly as shown at 54 to engage over its upper edge. To additionally connect the 110 pad to the holder the holder, which is preferably stamped from sheet metal, is provided with diametrically opposed V-shaped clefts 55 defining triangular shaped prongs 56 which are bent upwardly and passed 115 through the bottom of the pad and then rebent as clearly shown in Fig. 5. The holder 49 is provided with a second pair of V-shaped clefts 57 preferably diametrically opposed and defining triangular tongues 59 120 which are bent downwardly, passed through the bottom 43 of the box and rebent to anchor the holder to the box.

In view of the various modifications illustrated and described it will of course 125 be apparent that I do not wish to limit myself to any specific details of construction and I therefore reserve the right to make any changes within the scope of the appended claims.

Having thus described the invention, what is claimed as new is:

1. The combination with a box having a peripheral wall and a compressed powder holder having an upwardly and inwardly inclined peripheral wall, of an anchoring device adapted to seat in the bottom of the box and having upwardly and inwardly directed resilient fingers adapted to lockingly 10 yet detachably receive the holder.
2. The combination with a box having a peripheral wall and a compressed powder holder having an upwardly and inwardly inclined peripheral wall, of an anchoring 15 device adapted to seat in the bottom of the box and having upwardly and inwardly directed resilient fingers adapted to lockingly yet detachably receive the holder, the anchoring device being proportioned for wedging 20 engagement within the peripheral wall of the box.
3. The combination with a box having a slightly flared peripheral wall and a powder holder adapted to seat in the box and 25 having an upwardly and inwardly inclined peripheral wall, of a substantially disk

shaped body of sheet material adapted to be wedged within the flared wall of the box and slotted radially at peripherally spaced intervals to provide resilient tongues which 30 are bent upwardly and inwardly to detachably engage the inwardly directed wall of the holder.

4. The combination with a container and a compressed powder pad, of a resilient 35 plate sprung into the container to seat flatly against the bottom thereof and be frictionally held therein, and locking fingers projecting from the plate and engaging the 40 pad.

5. A holder for powder pads comprising a resilient plate having radially extending ears, the plate at either side of each ear being radially slotted whereby the ears, together with the portions comprehended between 45 the slots, provide resilient tongues, the tongues being upwardly and inwardly bent to extend at an acute angle to the plate and the terminals of the tongues being out bent.

In testimony whereof I affix my signature.

WILLIAM G. KENDALL. [L. S.]
